UNITED STATES PATENT OFFICE.

THOMAS F. HATHAWAY, OF ELGIN, ILLINOIS, ASSIGNOR TO ELGIN AMERICAN MANUFACTURING COMPANY, OF ELGIN, ILLINOIS, A CORPORATION OF ILLINOIS.

CIGARETTE-CASE.

1,189,813.

Specification of Letters Patent. Patented July 4, 1916.

Application filed November 24, 1915. Serial No. 63,215.

To all whom it may concern:

Be it known that I, THOMAS F. HATHAWAY, a citizen of the United States, residing at Elgin, in the county of Kane and State of Illinois, have invented certain new and useful Improvements in Cigarette-Cases, of which the following is a specification.

The cigarette case of the present invention belongs to that class which employs an inner container having pockets adapted to each receive a single cigarette.

One object of the invention is to so mount and hinge the leaves comprising the container that the latter will maintain a position substantially at right angles to the case when the case is laid open, thereby facilitating withdrawal of the cigarette; and the invention further relates to the spring arrangement in the hinge for throwing the case into open position when unlocked, and to the arrangement of the hinge in such a manner as to afford a mounting both for the sections of the case and the leaves of the container.

The invention further relates to the formation of the container in such a manner as to facilitate manual withdrawal of the cigarettes and to the details of the construction hereinafter described and claimed.

In the drawing:—Figure 1 is a perspective view showing the case laid open, and illustrating the manner of withdrawing the cigarettes from the container; Fig. 2 is a vertical sectional view; Fig. 3 is an enlarged plan view of the same; and Fig. 4 is a perspective detail of the hinge.

The case comprises outer rectangular sections 5 dished in the usual manner. One of the sections is provided with a snap lock 6 to hold the case closed when the sections are brought together. Each of the sections along its inner edge is formed to provide a plurality of tubular sleeves 7 which are alined to receive a pintle 8, which affords the pivotal mounting of a hinge for uniting the parts. Near each end of the pintle a space is provided between the adjacent sleeves to afford a mounting for the companion leaves 8^a of the cigarette container 9. Each of the leaves is provided near each end with a sleeve 10, which is alined with the sleeves 7 of the case sections and mounted upon the pintle 8, which thus furnishes a hinge mounting for the four principal parts comprising the case.

As shown in Fig. 3, each of the sleeves 7 is partially cut away at the point 11 to afford a stop or abutment 12 which cooperates with a similar stop or abutment 13 on the adjoining leaf sleeve. A similar co-operating arrangement is provided at the opposite end of the hinge between the remaining case section and the remaining leaf section, with the result that, when the sections of the casing have been laid open into horizontal or flatwise position, as shown in Fig. 1, the co-operating stops will come in contact with one another and maintain each of the container leaves in right angled relation with respect to the adjacent section 70 of the casing. In other words, each of the leaves is afforded freedom of movement with respect to the adjoining section of the casing through an arc of about 90 degrees, at which time the stops will come into contact to limit 75 any further relative movement of the parts, as best shown in Fig. 4.

In order to facilitate the opening of the sections of the casing and also to maintain the container leaves in closed relation with 80 respect to one another and in right angled relation with respect to the sections of the casing, a pair of coil springs 14 are employed which are mounted to surround the pintle in suitable spaces afforded for the purpose. 85 One of the coil springs is arranged to have its ends bear against one of the case sections and the co-operating container leaf, and the other spring is arranged to bear against the remaining case section and its co-operating container leaf. The arrangement is one which causes the sections of the casing to fly back into parallel horizontal relation when the spring lock is pressed, and at the same time maintains the two leaves comprising the cigarette container in closed position under spring tension, but permits the latter to be spread apart, against the tension of the springs, when it is desired to open up the container for the purpose of inserting 90 100 the cigarettes.

The leaves composing the container are grooved or channeled, as shown, to afford individual pockets for the cigarettes, and each pocket, so formed, is provided on each side 105 with an elongated slot 15 which exposes the body of the cigarette on each side and facilitates withdrawal of the cigarettes between the thumb and finger in the manner indicated in Fig. 1.

The arrangement is one which simplifies the construction by reducing the number of parts to a minimum, and by mounting all of the parts upon a single pintle, thus facilitating the assembling of the parts, and at the same time affording a most efficient and desirable form of hinge mounting.

I claim:

1. A cigarette casing comprising two sections, a pintle for hinging the sections together, an inner container consisting of two leaves hinged upon the same pintle, and cooperating stops between each casing section and one of the leaves for limiting the movement of one with respect to the other, substantially as described.
2. A cigarette casing comprising two sections, a pintle for hinging the sections together, an inner container consisting of two leaves hinged upon the same pintle, cooperating stops between each casing section and one of the leaves for limiting the movement of one with respect to the other, and springs for bearing against the casing sections for forcing said casing open, and maintaining the leaves in closed relation, substantially as described.
3. A cigarette casing comprising two sections, a pintle for hinging the sections together, an inner container consisting of two leaves hinged upon the same pintle, cooperating stops between each casing section and one of the leaves for limiting the movement of one with respect to the other, and a coil spring interposed between each casing section and its cooperating container leaf for forcing back the sections into open position, and maintaining the leaves in closed

relation with respect to one another, substantially as described.

40

4. A cigarette casing comprising two sections having alined sleeves, a pintle entered through said sleeves to hinge the parts together, an inner container consisting of two leaves having alined sleeves mounted upon the pintle, a coöperating pair of stops upon the adjoined sleeves of each casing section and the adjacent leaf for limiting the relative opening movement of the parts, and a pair of springs each bearing against one of the casing sections and the adjoining container leaf for forcing open the casing sections, and maintaining the container leaves in closed relation, substantially as described.

45

5. A cigarette casing comprising two sections, a pintle on which the sections are hinged, an inner container comprising two leaves each independently hinged on the same pintle, and springs for bearing against the casing sections and leaves for forcing the casing open and maintaining the leaves in closed position, substantially as described.

55

6. A cigarette casing comprising two sections, a pintle on which said sections are mounted, an inner container comprising two leaves each independently hinged on the same pintle, and a pair of springs, each spring having one end bearing against one of the casing sections and its other end bearing against the adjoining leaf section, substantially as described.
